UNITED STATES PATENT OFFICE.

G. W. GARDNER, OF TROY, NEW YORK.

SHAKER-BAR OF STOVE-GRATES.

Specification of Letters Patent No. 16,538, dated February 3, 1857.

To all whom it may concern:

Be it known that I, GEO. W. GARDNER, of Troy, in the county of Rensselaer and State of New York, have invented certain new and 5 useful Improvements in Constructing and Arranging Stove-Grates and Their Appendages; and I do hereby declare that the following is a full, clear, and exact description of the same, reference being had to the annexed drawings, making a part of this specification, in which—

Figure 1 is a plan view. Fig. 2 is a sectional view taken at the line $w-w$ of Fig. 1 and Fig. 3 is a sectional view taken at the 15 line $x-x$ of Fig. 1; the same letters having reference to like parts in each of the figures.

The nature of my invention consists in making the shaker bar to operate on a fulcrum at, or in the rim of the stove, thus 20 avoiding the extended slot usually made in stoves for the shaker bar to move in when the fulcrum is at the center of the grate; as hereinafter described.

The description of my improvement is as 25 follows: A is the base plate of an air heating stove.

B is the grate attached in such a manner to the rock shaft C, by the pin or pivot (a), as to allow the grate a free horizontal 30 vibrating motion when needed; this rock shaft at the place where the grate is attached to it, is swelled, or enlarged out into a circular form as shown by the dotted lines Fig. 1, which form prevents the pivot (a) from 35 working loose when rocking the grate.

D is a cast iron expansion ring plate, which rests upon projections (b b) cast upon the base plate; this ring encircles the grate, and lying over the rock shaft serves to keep 40 the rock shaft and grate in their proper bearings and positions; and permits a vertical vibrating motion to be given to the grate when desired. This ring plate, also serves the purpose of a base, or support to the fire 45 brick lining of the furnace, and is so constructed and arranged in regard to the base

plate, as to leave a small space (c), between it and the base plate, into which space the ring plate expands by the heat of the fire, without coming in contact with the sides of 50 the base plate, and receiving the first and most intense action of the fire, it shields and protects the base plate from being cracked by the sudden unequal expansion of the plate by heat.

(d) is a stop or rest cast upon the base plate, for one edge of the grate to lie upon when at rest, which side or edge is made the most heavy, so as to cause it to rest upon 55 that side.

E is the shaker bar. In the base plate at (e), is cast a hole of sufficient size to receive, hold, and serve the enlarged part of the bar at (f), as a fulcrum; while a horizontal motion is given to the grate.

(g g) are projections cast upon the under side of the grate, for the purpose of holding the end of the shaker bar, while vibrating the grate; this method of constructing and using the shaker bar prevents any dust or 60 ashes from getting into the apartment when shaking the grate.

By means of the fulcrum (f), in my shaker bar, I am able to revolve the grate B sufficiently without the extended slot, in the 65 rim of the stove, for the shaker bar, in ordinary grates to move; thus confining the dust, and ashes, in the stove while revolving the grate.

Having thus fully described my improvements in stove grates and appendages thereto, what I claim therein as new, and desire to secure by Letters Patent, is:

The shaker bar E with the fulcrum for its equivalent, as described for the purpose of 85 revolving the grate, without the usual slot in the stove; and confining the ashes in the stove, as set forth.

GEO. W. GARDNER.
